REPEATING FUSE CONSTRUCTION

John B. Hendricks, Hales Corners, Wis., assignor
to Line Material Company, South Milwaukee,
Wis., a corporation of Delaware

Application April 9, 1934, Serial No. 719,650

38 Claims. (Cl. 200—126)

This invention relates to a repeating fuse construction and is particularly directed to a construction in which a device is provided which recloses the circuit after the blowing of a fuse 5 and connects a fresh or reserve fuse in the circuit, such device being capable of repeating as many times as the device as designed for.

The advantage of this automatic repeating fuse construction is that the device lends itself 10 to transmission service and customer's substation service. Frequently in these services short-circuits occur due to any one of many causes, such as a tree falling across a pair of lines, a pair of lines being whirled together by a wind, 15 a flashover, a temporary ground, or the branch of a tree which in a violent wind may be blown against the line. Under these and similar conditions it frequently happens that the trouble is only temporary and that it either ceases 20 of itself or the fault is burned out almost immediately.

This invention is designed to provide a device which will take care of conditions such as outlined above, which will electrically disconnect 25 the blown fuse from the line, and after a predetermined brief interval immediately connect a reserve or fresh fuse in the line, such device providing for the successive operation of as many fuses as the device is equipped to handle, and to 30 provide a device of this type in which the time delay interval is automatically secured from the inherent characteristics of the device itself without requiring any auxiliary timing mechanism.

This invention provides for the renewal of a 35 blown fuse without interrupting the service, and objects of this invention are to provide a construction which permits the ready removal and refusing of the blown fuse, which permits the ready restoring of such refused fuse, and the 40 automatic disconnecting of the next adjacent auxiliary or reserve fuse without at any time interrupting the circuit during this restoring operation.

A primary object of this invention is to provide 45 a housed type of drop-out repeating fuse construction in which as many of the housed types of fuses may be related as required for the given number of repetitions elected, and in which although each fuse is housed, nevertheless it drops 50 out of position after blowing and opens the door of its particular housing, thus giving a visual indication of the particular fuse that has blown.

Further objects of this invention are to provide 55 a construction in which no fuse has to be first mechanically moved into place before it is

ready to operate upon the blowing of a preceding or first fuse, in which the auxiliary or reserve fuses although mechanically in place are nevertheless automatically electrically connected in service in succession as the preceding fuse or 5 fuses blow.

Further objects are to provide a construction in which the repeating, housed, multiple fuse is provided, and in which any door may be separately opened without moving the fuse out of place 10 if desired, and in addition in which any fuse may be automatically tripped so that it will drop out of position as desired.

Further objects are to provide a construction in which the blown fuse or fuses may be readily 15 removed, refused, and replaced and when rocked into position, will automatically disconnect the succeeding fuse.

An embodiment of the invention is shown in the accompanying drawings, in which:

Figure 1 is a vertical sectional view through one 20 of the drop-out fuses of the repeating fuse construction, such view corresponding to a section on the line 1—1 of Figure 1.

Figure 2 is a sectional view on the line 2—2 of 25 Figure 1.

Figure 3 is a view showing a plurality of fuses arranged in the cooperating relation for repeating action.

Figure 4 is a view, partly in section, looking 30 from the front of one of the fuses.

Figure 5 is a sectional view on the line 5—5 of 35 Figure 4.

Figure 6 is a sectional view on the line 6—6 of Figure 4.

Referring to the drawings, particularly Figure 35 3, it will be seen that a series of these individual housed drop-out fuses are provided and are indicated generally at A, B, and C. Each of these drop-out fuses comprises a porcelain casing or 40 housing 1 provided with a hinged door 2. The housing is provided with any suitable means of attaching it to a support, such as the bolt construction indicated at 3. Each housing is provided with an upper terminal member 4 and 45 a lower terminal member 5. The upper terminal member 4 is provided with a pair of spaced spring arms 6 between which the upper contact 7 of the fuse is adapted to be forced, as shown in Figures 1 and 4. The upper portion of the 50 fuse is detachably attached to the door 2.

One form of the attachment is shown in the drawings, and it will be noted that the upper terminal is provided with an upwardly projecting 55 forwardly located hook 8 which is engaged

by a lip 9 carried by the door and rotatable by means of the wing nut or manipulating member 10. It is obvious that if desired, the door may be detached from the fuse by rotating the lip 9 out of engagement with the hook and thereafter the door may be swung downwardly about its pivot 11.

Each of the upper terminal members of the successive fuses are permanently electrically connected to the line 12.

The lower terminal member 5 is provided with a brush or yielding contact 13, see Figure 1, which bears against the lower contact 14 carried by the expulsion fuse tube 15. The lower terminal member is also provided with forwardly projecting arms on opposite sides of the lower contact 14. As shown in Figure 3, the lower of these pairs of arms is provided with a hooklike portion 16 which receives the pivot pin 17 carried by the lower contact member 14 of the expulsion fuse. Each of the upper arms 18 is provided with an outwardly turned foot 19, as shown most clearly in Figure 4.

It is apparent that when the fuse rocks about its pivot point 17 that the door rocks about its pivot point 11 and the tongue 9 is thus lifted from the hook 8, the door dropping downwardly to the dotted line position shown in Figure 1 and the fuse dropping outwardly to its dotted line position shown in such figure.

The lower contact 14 of the fuse carries a hammer or tripping member 20 which is urged by means of a spring 21 in a clockwise direction, as viewed in Figure 1. This hammer receives the lower end of the fuse link 22, so that when the fuse link is ruptured, the hammer 20 suddenly swings towards the dotted line position shown in Figure 1. The purpose of this hammer or tripping member will be apparent as the description proceeds.

The fuse tube 15 is provided with an intermediate member or collar 23, see Figure 1, which has spaced arms 24 between which a pin 25 is carried. This pin is normally engaged by the hook of a latch 26, as shown in Figure 1. This latch is normally in the full line position shown in Figure 1 and is retained in this position under normal conditions by the weight of the downwardly extending rod 27 pivotally attached to the arm 28 of the latch, the latch being in the form of a latch lever and being pivoted as indicated at 29 between suitable brackets 30 carried by the rear face of the casing. The rod or plunger 27 is provided with a stop collar 31 which limits its downward motion. It is to be observed from Figure 1 that the forward face of the latch is cam-shaped or bevelled, as indicated at 32, so that when the fuse is rocked to operative position, as shown in full lines in Figure 1, the pin 25 or catch will ride along the cam face 32 of the latch, thus depressing it, the latch thereafter moving upwardly into latching position.

The arm 27 terminates in an anvil portion or outwardly turned portion 33 which is in the path of movement of the spring pressed trip hammer 20, so that when the hammer is tripped by the blowing of the fuse link 22, it swings upwardly and strikes the anvil portion 33, thus opening the latch and allowing the fuse and door to drop outwardly.

Provision is made for the manual release of the fuse if such release is desired. This is readily accomplished by providing an insulating rod 34 which preferably terminates in an insulating handle 35 projecting slightly below the bottom of

the fuse box. The rod 34 is attached in any operative manner to the rod 27, as by means of the yoke 36 shown in Figure 2, so that when the plunger or member 35 is pressed upwardly, the latch is released and the fuse drops outwardly.

In order to connect a succeeding fuse, a switch arm 37 is provided which is normally out of engagement with a stationary contact 38, see Figure 6, a conductor 39 leading from the contact 38 to the lower terminal of the next succeeding fuse, as indicated in Figure 3. The switch arm 37 and stationary contact 38 are carried in an outwardly projecting housing 1' preferably integral with the housing 1 and closed by a removable door or plate 40, see Figure 4. This plate is held in place by any suitable means, as by a thumb screw 41. It is preferable to provide a slotted flange 42 which receives the conductor 39 in its slot and which fits beneath a lip 43 formed integrally on the housing 1.

An inverted U-shaped yoke 44, see Figures 1, 4 and 5, is rigidly attached to pivoted trunnions 45 and 46, as shown most clearly in Figure 4. This yoke is spring pressed outwardly by means of the springs 47, see Figures 4 and 5. The trunnion or shaft 46 is rigidly attached to the switch arm 37, see Figure 4, so that when the trunnion rocks forwardly, the switch arm 37 engages the stationary contact 38 and thus connects the lower terminal of the succeeding fuse to the conductor 39.

The yoke 44 engages the stop arms or feet 19 of the lower terminal 5 and thus electrically connects the line 48, see Figure 3, to the lower terminal of the succeeding fuse. Obviously the yoke could be connected to the lower terminal member by a flexible leader, not shown, or by any other means desired. Normally, however, the yoke 44 is held in its rearmost position by the fuse tube 15 which is located in front of the yoke, as is obvious from Figures 1 and 4.

It is apparent that when a temporary short-circuit occurs on the line, that the first fuse will blow. Frequently, however, these short-circuits clear themselves almost instantly, as previously pointed out, and a certain interval of time occurs before the next fuse is thrown in due to the fact that a certain interval of time is required for the device to drop from its full line position to the dotted line position shown in Figure 1. If the fault has cleared itself, the succeeding fuse will not blow, but if it has not cleared itself, the succeeding fuse will blow.

A few of the fuses have been shown in Figure 3 in the relation that they occupy in practice, but it is obvious that as many may be used as desired.

If for any reason it is desired to have the fuse drop out of position, this may be accomplished manually by pressing upwardly on the plunger 35, see Figure 1, thus releasing the latch and allowing the fuse and door to drop outwardly. On the other hand, if it is desired to inspect the interior of the fuse boxes or housings, the door alone may be opened outwardly after turning the lip 9 upwardly to a vertical position.

Further, suppose one or more of the fuses blow and the fault is cleared and a succeeding fuse remains in circuit. Obviously, the blown fuse or fuses may be readily detached from the hooklike members 16, see Figure 5, and may be refused and replaced. Thereafter the fuse is rocked into closed position by a suitable member or by merely rocking the door into closed position. The latch will then engage the catch carried by the fuse and

retain the fuse in service position. As the fuse moves into service position, it automatically disconnects the next succeeding fuse, as previously described, as the switch arm 31 moves out of engagement with the contact 38.

It will be seen that a simple type of drop-out housed repeating fuse has been provided in which the blown fuse may be refused and replaced and moved back into service without interrupting the 10 service through the fuse then remaining in operation. Further, it will be seen that as many of these fuse units as desired can be used.

Although this invention has been described in considerable detail, it is to be understood that 15 such description is intended as illustrative rather than limiting, as the invention may be variously embodied and is to be interpreted as claimed.

I claim:

1. A drop-out fuse comprising a fuse tube having spaced contacts thereon, supporting means having stationary contacts normally engaging said spaced contacts, a fuse link electrically joining said spaced contacts, latch means restraining said tube against movement away from said stationary contacts, and a hammer for imparting a releasing blow to said latch means, said hammer being biased towards latch releasing movement and restrained against motion by said fuse link, whereby when said fuse link is ruptured, said 30 hammer will release said latch means, said fuse tube, fuse link and hammer constituting a unit and being assembled before said stationary contacts are electrically connected.

2. In a fuse construction, a pair of stationary 35 contacts, a fuse tube having spaced contacts normally engaging said stationary contacts, pivotal means for supporting said fuse tube adjacent its lower end, trigger mechanism carried by said fuse tube, a fuse link joining said spaced contacts and 40 normally restraining said trigger mechanism against motion, latch means for holding said fuse tube in position with the spaced contacts in engagement with said stationary contacts, said latch means being releasable by said trigger mechanism when said fuse link is ruptured, said 45 trigger mechanism being biased towards latch releasing motion, and manually operable means for releasing said latch means independently of said trigger mechanism, said manual means including a manipulating member projecting outwardly and 50 spaced from said fuse tube.

3. A housed type of drop-out fuse comprising a casing, a door for said casing, a pair of stationary 55 contacts carried by said casing, a fuse tube mounted within said casing and having spaced contacts normally engaging said stationary contacts, a fuse link normally electrically connecting said spaced contacts, and operative means normally holding said door closed, said operative 60 means being biased towards releasing motion and being normally restrained against such motion by said fuse link, whereby when said fuse link is ruptured, said door will move outwardly away from said fuse tube.

4. A housed type of drop-out fuse comprising a casing, a door pivotally mounted adjacent its lower portion and normally closing said casing, said casing having a pair of stationary contacts, a fuse tube mounted within said casing and having spaced contacts normally engaging said stationary contacts, a fuse link electrically connecting said spaced contacts, and means releasably 70 operatively connecting said door and said fuse tube and controlled by said fuse link, whereby

when said fuse link is ruptured, said door will swing outwardly away from said fuse tube.

5. A housed type of drop-out fuse comprising a casing having stationary contacts, a door for said casing movable outwardly from said casing, a fuse 5 tube mounted within said casing and having spaced contacts normally engaging said stationary contacts, interlocking means between said fuse tube and said door, latch means normally holding said fuse tube in operative position and 10 maintaining the interlocking of said door and said fuse tube, and mechanism for releasing said latch means and controlled by said fuse link, whereby when said fuse link has ruptured, said latch means is released and the interlocking relation between said door and fuse is terminated. 15

6. A housed type of drop-out fuse comprising a casing, a door hingedly supported from said casing and adapted to rock outwardly and downwardly from said casing, said casing having stationary contacts, a fuse tube movably mounted within said casing and having spaced contacts normally engaging said stationary contacts, a fuse link electrically joining said spaced contacts, means normally holding said door to said fuse tube and releasable upon motion of said fuse tube, latch mechanism normally holding said fuse tube in operative position, and means controlled by said fuse link for releasing said latch mechanism when said fuse link is ruptured. 30

7. A housed type of drop-out fuse comprising a casing having stationary contacts, a door movably supported by said casing, a fuse tube having spaced contacts normally engaging said stationary contacts, a fuse link electrically joining said spaced contacts, means biased towards releasing motion and normally restrained by said fuse link for releasably holding said fuse tube in operative position, and externally operable movable means carried by said door for releasably locking said 40 door to said fuse tube. 35

8. A housed type of fuse comprising a casing having stationary contacts, a door hingedly supported from said casing, a fuse tube mounted within said casing and having spaced contacts normally engaging said stationary contacts, a fuse link electrically joining said spaced contacts, a catch carried by said fuse tube, and locking means carried by said door and operable externally of said door for engaging the catch carried 50 by said fuse tube, whereby said door may be unlocked from said fuse tube and opened without disturbing said fuse tube, and whereby said fuse tube and said door may be bodily moved outwardly together. 55

9. A housed type of drop-out fuse comprising a casing having stationary contacts, a fuse tube pivotally supported adjacent its lower end within said casing and having spaced contacts normally engaging said stationary contacts, a fuse link 60 electrically joining said spaced contacts, trigger mechanism biased towards releasing motion and normally restrained by said fuse link, latch means normally holding said fuse tube in operative position and releasable by said trigger mechanism 65 when said fuse link is ruptured, a door for said casing, detachable interlocking means between said door and said fuse tube, and a manually manipulable member projecting from said casing for tripping said latch means independently of 70 said trigger mechanism.

10. A housed type of drop-out fuse comprising a casing having stationary contacts, a fuse tube pivotally supported adjacent its lower end within said casing and having spaced contacts nor- 75

5 mally engaging said stationary contacts, a fuse link electrically joining said spaced contacts, trigger mechanism biased towards releasing motion and normally restrained by said fuse link, latch
5 means normally holding said fuse tube in operative position and releasable by said trigger mechanism when said fuse link is ruptured, a door for said casing, detachable interlocking means between said door and said fuse tube externally
10 opérable, and a manually manipulable plunger projecting from said casing for tripping said latch means independently of said trigger mechanism.

11. A housed type of fuse comprising a casing having stationary contacts, a fuse tube normally held in operative position and having spaced contacts normally engaging said stationary contacts, a fuse link electrically joining said spaced contacts, a door for said casing, a catch carried by said fuse tube and located on the side thereof towards said door, a movable latch carried by said door and normally engaging said catch, and external means carried by said door for releasing said latch, whereby said door may be moved outwardly either independently of said fuse tube or
25 said fuse tube and said door may be moved outwardly together.

12. A repeating fuse construction comprising a first fuse unit and a second fuse unit, a fuse link in each unit, an electric line normally connected through said first fuse unit, each fuse unit including a fuse tube for the fuse link mounted to drop outwardly when said fuse link is ruptured, and a switch biased towards closed position and normally held in open position by the tube of the first fuse unit, said switch upon closing connecting the second fuse unit in the electric line.

13. A repeating fuse construction comprising a first fuse unit and a second fuse unit, a fuse link in each unit, an electric line normally connected through said first fuse unit, each fuse unit including a fuse tube for the fuse link mounted to drop outwardly when said fuse link is ruptured, and a switch biased towards closed position and normally held in open position by the tube of the first fuse unit, said switch upon closing connecting the second fuse unit in the electric line, said switch forming a unitary structure with said first fuse unit.

14. A repeating fuse construction comprising a first fuse unit and a second fuse unit, a fuse link in each fuse unit, an electric line normally connected through said first fuse unit, said first fuse unit including a casing having stationary contacts, a fuse tube for the fuse link mounted to drop outwardly when said fuse link is ruptured, a normally open switch carried by said first fuse unit for connecting said second fuse unit in the electric line and closable when the fuse tube of the first fuse unit drops outwardly, and a housing for said switch formed as a unitary structure with the casing of said first fuse unit, the casing of said first fuse unit being provided with a main door to give access to the fuse tube of said first fuse unit and the housing for said switch being provided with a door to give access to said switch.

15. In a repeating fuse construction, a plurality of units arranged for sequential operation, said units including casings, drop-out fuse assemblies each having a fuse link, latch means normally restraining its fuse assembly from outward motion and controlled by the fuse link of such assembly, a switch carried by each succeeding fuse unit as a unitary portion thereof

and automatically actuated upon the outward motion of its fuse assembly for connecting the next succeeding fuse unit in circuit, and manually operable means for releasing the latch means for each fuse assembly.

16. A repeating fuse construction comprising a series of fuse units each fuse unit comprising a unitary structure including a casing having stationary contacts and a fuse tube having spaced contacts normally engaging said stationary contacts and movable away from said stationary contacts, a fuse link in each fuse tube normally electrically joining said spaced contacts and restraining the corresponding fuse tube against motion away from the stationary contacts, a door for each casing movable outwardly from the casing when the fuse tube moves away from the stationary contacts, an electric line normally connected through the first of said series of fuse units, said first fuse unit at least, having a normally open switch for connecting a succeeding fuse unit in the electric line and closable when the tube of the first fuse unit moves away from the stationary contacts of the first fuse unit, said switch being opened when the fuse tube of the first fuse unit is moved into operative position by the closing of the door of the first fuse unit.

17. A repeating fuse construction comprising a series of unitary fuse units, each fuse unit comprising a casing having stationary contacts and a door and fuse assembly including a fuse tube having spaced contacts normally engaging the stationary contacts and having a fuse link normally electrically joining the spaced contacts of the fuse tube, said door and fuse assembly being movable away from said stationary contacts, means controlled by the fuse link for restraining the door and fuse assembly against motion, an electric line normally connected through the first of said series of fuse units, at least said first fuse unit having a normally open switch closable when the fuse and door assembly of said first fuse unit moves away from said stationary contacts to connect a succeeding fuse unit in said electric line, said switch being opened when the door and fuse assembly of said first fuse unit is moved back to its original position.

18. A repeating fuse construction comprising a first fuse unit and a second fuse unit, a fuse link in each fuse unit, an electric line normally connected through said first fuse unit, said first fuse unit including a fuse tube for the fuse link, said fuse tube being mounted to drop outwardly when said fuse link is ruptured, a normally open switch movable to closed position when said first fuse unit blows, said switch upon closing connecting said second fuse unit in the electric line, and switch opening means operatively connected with said switch and arranged in the path of return movement of said first fuse unit when said first fuse unit is rocked back to operative position, said means directly opening said switch upon the backward rocking motion of said first fuse unit.

19. A repeating fuse construction comprising a first fuse unit and a second fuse unit, a fuse link in each fuse unit, an electric line normally connected through said first fuse unit, said first fuse unit including a fuse tube for the fuse link mounted to rock outwardly and downwardly when said fuse link is ruptured, a switch closable upon outward dropping motion of said first fuse unit to connect the second fuse unit in the electric line, and switch opening means operatively

connected to said switch and arranged in the path of return movement of said first fuse unit for opening said switch by the direct rearward closing motion of said first fuse unit.

- 5 20. A repeating fuse construction comprising a first fuse unit and a second fuse unit, a fuse link for each fuse unit, an electric line normally connected through said first fuse unit, said first fuse unit including a fuse tube for the fuse link, 5
10 said fuse tube being pivoted for outward motion upon blowing of said first fuse unit, means normally restraining said first fuse unit against outward motion, a switch biased towards closed position and normally held in open position by said 15
15 first fuse unit, said switch upon closing connecting the second fuse unit in the electric line, and switch opening means operatively connected to said switch and normally arranged rearwardly of said first fuse unit, said switch opening means 20
20 being engaged by the tube of said first fuse unit when said first fuse unit is rocked back into operative position, said switch operating means opening said switch upon the reclosing of said first fuse unit.

- 25 21. A repeating electrical device comprising a first cut-out and a second cut-out, an electric line normally connected through said first cut-out, said first cut-out having stationary contacts and a fuse tube having spaced contacts normally 25
30 engaging said stationary contacts, a fuse link electrically connecting said spaced contacts, said fuse tube being mounted for motion away from at least one of said stationary contacts and being restrained against outward motion by means 30
35 controlled by said fuse link, a switch closable upon outward motion of said fuse tube to connect the second cut-out in the electric line, and switch opening means operatively connected to said switch and arranged in the path of return 35
40 movement of said fuse tube for opening said switch by the force exerted upon said means by the rearward motion of said fuse tube.

22. A repeating electrical device comprising a first cut-out and a second cut-out, an electric 40
45 line normally connected through said first cut-out, said first cut-out having stationary contacts and a fuse tube having spaced contacts normally engaging said stationary contacts, a fuse link electrically connecting said spaced contacts, casting means enclosing at least said first cut-out, said fuse tube being mounted for motion away from at least one of said stationary contacts and being restrained against outward motion by 45
50 means controlled by said fuse link, a switch closable upon outward motion of said fuse tube to connect the second cut-out in the electric line, and switch opening means operatively connected to said switch and arranged in the path of return movement of said fuse tube for opening said 50
55 switch by the force exerted upon said means by the rearward motion of said fuse tube.

23. A repeating electrical device comprising a first cut-out and a second cut-out, an electric line normally connected through said first cut-out, said first cut-out having stationary contacts and a fuse tube having spaced contacts normally engaging said stationary contacts, a fuse link electrically connecting said spaced contacts, casting means enclosing at least said first cut-out 60
65 and having a door, means controlled by said fuse link for releasing said door and said fuse tube upon rupture of said fuse link, said fuse tube and said door being movably mounted with reference to said casing means, switch means controlled by 65
70 the position of said fuse tube for connecting the

electric line through said second cut-out when said first cut-out has blown, and switch opening means operatively connected to said switch and arranged in the path of return movement of said fuse tube and adapted to be moved to open said 5
5 switch by the direct rearward motion of said fuse tube.

24. In a repeating fuse construction, a first fuse unit including a pivotally mounted fuse tube and a fusible element therein, said tube being 10
10 releasably held in circuit closing position until said element is fused, a second fuse unit, a circuit closing switch biased towards circuit closing position for closing a circuit through the second fuse unit, latching means operable independently of 15
15 said fusible element and holding said switch in open circuit position, and latch releasing means carried by said tube and operatively engageable with said latching means when said element has fused, thereby to release said switch for circuit 20
20 closing movement.

25. In a circuit interrupting and closing device, a first interrupting unit including a pivotally mounted arcing tube, circuit rupturing means within said tube, releasable means holding said tube in circuit closing position and operative on overload to release said tube; a second interrupting unit, a circuit closing switch biased towards circuit closing position for closing a circuit through the second interrupting unit, a second 25
30 releasable means holding said switch in open circuit position, and means carried by said tube for operatively engaging said second releasable means to release said switch after the circuit has 30
35 been interrupted within said tube.

26. In a repeating electrical device of the class described, a housing, a door for said housing, said housing having an open bottom, stationary contacts mounted within said housing, an arcing tube mounted within said housing, current responsive means including an expulsive conductor within said tube for interrupting the circuit within said tube, said tube having a closed upper end and an open bottom end, the open bottom 40
45 end of said tube being located adjacent the opening in said housing, means normally holding said tube in circuit closed position and releasable upon the occurrence of an overload, said tube being movable when released from operative to inoperative position, and a circuit closing switch 50
55 controlled by said tube when said tube moves from operative to inoperative position.

27. In a repeating electrical device of the class described, housing means having a plurality of separate compartments each provided with an opening adjacent the lower portion thereof, an electrical cut-out in each of said compartments, at least one of said electrical cut-outs including an arcing tube and current responsive means including an expulsive conductor located within 60
60 said arcing tube for interrupting the circuit within said arcing tube, means released upon the occurrence of an overload for releasing said tube, said tube being movably mounted and moving from operative to inoperative position upon the occurrence of an overload, and a switch controlled by said tube, said switch being normally open and closing the circuit through the succeeding cut-out.

28. In a fuse construction, a pair of stationary contacts, a fuse tube having spaced contacts thereon normally engaging said stationary contacts, a fuse link within said fuse tube electrically joining said spaced contacts, pivotal means for supporting said fuse tube adjacent its 70
75

lower end, latch means for holding said fuse tube in position with the spaced contacts in engagement with said stationary contacts, said latch means normally holding said fuse tube independently of said fuse link, and releasing means carried by said fuse tube and biased towards latch releasing motion and restrained against motion by said fuse link, said latch means being releasable by said releasing means when said fuse link is ruptured, said fuse tube, fuse link and said releasing means constituting a unit and being assembled before said stationary contacts are electrically connected.

29. In a fuse construction, a pair of stationary contacts, a fuse tube having spaced contacts thereon normally engaging said stationary contacts, a fuse link within said fuse tube electrically connecting the said spaced contacts, pivotal means for supporting said fuse tube adjacent its lower end, latch means for holding said fuse tube in position with the spaced contacts in engagement with said stationary contacts, releasing means carried by said fuse tube and biased towards latch releasing motion and restrained against releasing motion by said fuse link, said latch means holding said tube in position independently of said fuse link, said latch means being released by said releasing means when said fuse link is ruptured, and manually operable means for releasing said latch means independently of said releasing means, said fuse tube, fuse link and releasing means constituting a unit and being assembled before said stationary contacts are electrically connected.

35. 30. A fuse construction comprising a supporting member, a fuse tube movably supported by said supporting member, said supporting member having a pair of stationary contacts, said fuse tube having a pair of spaced contacts normally engaging said stationary contacts, a fuse link within said fuse tube electrically joining said spaced contacts, latch means independent of said fuse link for restraining said fuse tube against motion with reference to said supporting means, and releasing means for releasing said latch means, said releasing means being biased towards latch releasing motion and being restrained against motion by said fuse link, whereby when said fuse link is ruptured said releasing means will release said latch means.

50 31. The combination of a fuse unit having a fuse tube mounted for movement from circuit closing position to open circuit position, latch means normally holding said tube in circuit closing position, said fuse unit having a fusible element, means controlled by said fusible element for releasing said tube from said latch when said fusible element is ruptured, and a switch provided with a switch operating arm extending into the path of movement of said tube, said tube normally holding said switch in open circuit position.

32. A fuse construction comprising a support having terminal members, a fuse tube normally occupying an operative position and movable from operative position to inoperative position, said fuse tube having a fuse link normally electrically connecting said terminal members, latch means for holding said fuse tube against motion from operative to inoperative position, means controlled by said fuse link for rendering said latching means ineffective, whereby said fuse tube will move to inoperative position when said fuse link is ruptured, and a switch permanently biased towards switch closed position and re-

leased upon movement of said fuse tube from operative to inoperative position.

33. A repeating fuse construction comprising a first fuse unit and a second fuse unit, a fuse link in said first fuse unit, said first fuse unit including a tube movable between open circuit and closed circuit position and released for movement from closed circuit position by said fuse link, an electric line normally connected through said first fuse unit, a normally open transfer switch movable to closed position when said first fuse unit blows and being held in open circuit position by said first fuse unit, said switch upon closing connecting said second fuse unit in the electric line, and switch opening means operatively connected to said switch and arranged in the path of return movement of said first fuse unit when said first fuse unit is moved back to operative position, said means being engaged by said first fuse unit and the force imparted to said means by said first fuse unit being directly transmitted to said switch to open said switch.

34. A repeating fuse construction comprising a first fuse unit and a second fuse unit, a fuse link in said first fuse unit, said first fuse unit including a tube laterally movable into closed circuit position and outwardly movable into open circuit position and released for movement from closed circuit position by said fuse link, an electric line normally connected through said first fuse unit, a normally open transfer switch biased to closed position and movable to closed position when said first fuse unit blows and being held in open position by said first fuse unit, said switch upon closing connecting said second fuse unit in the electric line, and switch opening means operatively connected to said switch and arranged in the path of return movement of said first fuse unit when said first fuse unit is moved back to operative position, said means being engaged by said first fuse unit and the force imparted to said means by said first fuse unit being directly transmitted to said switch to open said switch.

35. In a repeating fuse unit, the combination of a plurality of fuse units, at least the first fuse unit comprising a casing having spaced stationary contacts, a fuse assembly including a door for said casing and a fuse tube, said fuse tube having an upper and a lower contact and a fuse link within said tube normally forming a connecting member between said upper and lower contacts, means operative automatically upon the blowing of the fuse link of the first fuse unit to displace that fuse unit into an inoperative position, an electric line normally connected through the first of said fuse units, and an automatic switch releasable by the motion of said first fuse unit for connecting the electric line through a successive fuse unit.

36. The invention as claimed in claim 35, wherein said switch includes means biasing the same towards closed position, and means released by the displacement of the first fuse unit to release said switch for movement by said biasing means.

37. A repeating electrical construction comprising a plurality of cutouts including at least a first cutout and a second cutout, said first cutout having a door and a fuse tube constituting jointly a fuse tube assembly, means for actuating said fuse tube assembly for opening the electric circuit through said first cutout by the mechanical motion of said fuse tube assembly from operative to inoperative position, means for normally

retaining said fuse tube assembly in operative position so long as the fuse link thereof remains intact, and a normally open switch biased towards closed position carried by said first cutout 5 for establishing connection through said second cutout upon blowing of said first cutout.

38. A repeating fuse construction comprising a first fuse tube assembly and a second fuse tube assembly, casing means for said fuse tube assemblies, said first fuse tube assembly including supporting means and a fuse tube carried by said supporting means and movable with respect to said supporting means, said first fuse tube assembly having spaced contacts and having sta-

tionary contacts normally engaged by said spaced contacts, said first fuse tube assembly being movable outwardly from operative to inoperative position, a fuse link carried by said first fuse tube assembly electrically connecting said spaced contacts, means normally restraining said first fuse tube assembly from moving from operative to inoperative position, and a door for said first fuse tube assembly, said door being movable outwardly by the outward motion of said first fuse tube assembly when said first fuse tube assembly has blown. 10
